UNITED STATES PATENT OFFICE

CHARLES W. ANDREWS, OF DULUTH, MINNESOTA, AND HERMAN A. BRASSET, OF CHICAGO, ILLINOIS, ASSIGNORS TO H. A. BRASSET & COMPANY, OF CHICAGO, ILLINOIS, A CORPORATION OF ILLINOIS

METHOD OF MANUFACTURING MIXED WATER GAS AND OIL GAS

Application filed August 18, 1926. Serial No. 129,866.

This invention relates to a new and improved method of manufacturing gas and more particularly to a method of gasifying the heavy oils and tars used in carbureting 5 or enriching gases.

The development of processes for the cracking of oils for the production of gasoline is resulting in a constant increase in the price of what have been commonly known as gas 10 oils since it has now become possible to crack such oils into gasoline and the heavier residuum. This heavier residuum, while cheaper than gas oil for use in the manufacture of gas presents many difficulties in its use in 15 the gas processes. In usual methods of operation the liquid hydrocarbons used in the carburetion are sprayed into a carburetor which consists of a chamber filled with highly heated brick checkerwork. These heavy 20 residual oils when sprayed into such a carburetor result in the deposit of a large portion of their released carbon upon the bricks forming the checkerwork. This deposit interferes with the operation of the carburetor 25 and renewals of the checkerwork are required at short intervals. This renewal is expensive and also results in shutdowns of the plant with resultant loss in production.

The volatilization of these heavy oils in 30 checkerwork of this character is very inefficient as it reverses the best process for the volatilization of such oils. In volatilizing heavy oils the most efficient process consists in subjecting them to a gradual increase in 35 temperature. This results in a fractional distillation, components which volatilize at each temperature passing off and not being subjected to subsequent higher temperature, and thus degradation of the fractions is pre- 40 vented. When the heavy oils are sprayed on hot brick work the oils are subjected suddenly to high temperatures and the more volatile components are broken down by these excessive temperatures, resulting in a low output 45 of enriching volatiles and in large deposit of solid carbon. Mechanical difficulties make it impractical to reverse the flow through the carburetor and thus subject the heavy oil to gradually increasing temperatures.

It is an object of the present invention to

provide a new and improved method for the carburetion or enrichment of gas by the distillation of heavy oils and tars.

It is a further object to provide a method of this character in which the enriching hydrocarbons are not first subjected to the highest 55 temperatures.

It is also an object to provide such a method in which the non-volatilizable constituents of the tar or oil may be recovered as coke.

It is an additional object to provide a method whereby such coke or solid residue of the enriching material may be gasified in the operation of the process either by direct gasification where formed or by utilization in the 60 main gasifying chamber.

Other and further objects will appear as the description proceeds.

We have illustrated in the accompanying drawings one preferred embodiment of an 70 apparatus adapted for carrying out our method. In the drawings:

Figure 1 is a vertical section through the apparatus; and

Figure 2 is a plan view of the apparatus. 75

The gas generator 11 is of a usual type for a generating water gas and is provided with a fuel charging opening 12 and with the air inlet passage 13 controlled by valve 14 and the steam pipe 15 controlled by the valve 16, 80 entering the upper end of the generator. The lower portion of the generator is provided with a grate 17 and with the air inlet passage 18 controlled by the valve 19 and steam inlet pipe 20 controlled by valve 21, 85 which enter the generator below the grate.

The upper portion of the generator is connected with a secondary generator 22 by the passage 23 which enters the upper portion of generator 22 tangentially, as shown in Figure 90 2. This passage is controlled by valve 24 and the valve seat is provided with the cleaning vent 25 discharging into the secondary generator 22. The gas generator 22 is similar in construction to the gas generator 11 95 and is provided at its upper end with the fuel charging opening 26 and the oil pipe 27 controlled by the valve 28. The lower portion of the generator is provided with the grate 29 and with the air inlet passage 30 100

controlled by valve 31 and steam pipe 32 controlled by valve 33.

The lower portions of the gas generators 11 and 22 are connected by passage 35 controlled by valve 35'. The upper portion of the generator 22 is connected by passage 36 with the upper end of the superheater 37. This superheater is filled with the usual brick work 38. The secondary air passage 39 leads into the passage 36 and is controlled by valve 40. The lower portion of the generator 22 is connected by passage 41 controlled by valve 42 with the lower end of the superheater 37.

15 The lower portion of superheater 37 also communicates with the upwardly extending passage 43, the upper end of which is controlled by the stack valve 44. The passage 45 leads to the water seal 46 from which the 20 passage 47 leads to any suitable gas treating, washing, holding, or using apparatus which has not been shown. If desired the waste heat boiler 48 may be connected to the lower portion of superheater 37 by passage 25 49, the upper end of the boiler discharging through a passage controlled by stack valve 50.

Generator 11 is provided with the beam 30 52 which is located immediately above the grate 17 and is carried by the drive ring 53 by which it is rotated. The drive ring 53 is driven by gear 54 and may be water cooled by means of water supplied through connection 55. The ash receiving ring 56 is carried by the drive ring 53 and ash may be removed by means of the adjustable scoop 57. The generator 22 is provided with a similar beam 58, drive ring 59, gear 60, wa- 35 ter connection 61, ash ring 62, and scoop 63.

40 The lower portion of the generator 11 is shown provided with the water cooling chamber 64 and the generator 22 with the similar chamber 65.

The generator unit 11 is also provided 45 with the pipe 66 controlled by valve 67 so that oil or other enriching hydrocarbon may be sprayed into this unit if desired.

Our improved method of operation may be carried out in the apparatus shown by operating the generator 11 in the usual manner as a water gas generator. The charge of fuel may be entirely coke or when starting up, coke may be charged in the lower portion and coal in the upper portion, the coal being 50 coked by the passage of the gases there- through during the operation. A mixture of coal and coke may be charged if found preferable, the type of charge being varied depending upon the character of the fuel 55 available.

The second generator is charged with coke when starting up the apparatus. Fires are 60 preferably started upon both grates and the fuel and generators heated up. During this period, both generators may be up blasted by

air introduced through the grates by pas- 7 sages 18 and 30, the valves 19 and 31 being opened. The valves 35' and 42 would be closed and the valve 24 opened. The air blast gases from generator 11 pass through 7 passage 23 into the upper portion of generator 22 and the gases from both generators then pass up through passage 36 into the upper end of the superheater 37. Secondary air may be introduced 8 through passage 39, valve 40 being opened, and the combustion of the blast gases completed in the superheater, much of their heat being taken up by the checkerwork in the superheater. The blast gases may be dis- 8 charged through the stack valve 44 or additional heat recovery may be had by means of the waste heat boiler 48, shown in Figure 2.

When down blasting in the generator 11, the valve 24 will be closed and valve 35' 8 opened. The air is introduced through pipe 13, valve 14 being opened. Valve 42 may be partly opened so that only part of the air blast gases of generator 11 may be sent through the fuel mass in the generator 22. 9 The portion of the gases sent through this second generator will be passed down through the superheater while the gases passing valve 42 will pass through the lower portion only 10 of the superheater. It will be understood 9 that air may be introduced below generator 22 to complete the combustion of the blast gases from generator 11. In this case the temperatures may be too great for usual 11 types of metal grates in generator 22 and special grates may be provided. It should be noted that the secondary generator 22 is never down blasted.

After the fuel masses in the two generators have reached the temperature proper for 1 operation, the air blasting is stopped. The air valves are closed and valve 35' is closed and valve 24 is opened. Steam is introduced in the lower portion of generator 11, valve 21 in pipe 20 being opened. This steam 1 passes up through grate 17 into the incan- 1 descent carbonaceous residue in the lower portion of the generator 11 and water gas is generated. This hot water gas passes up through the fuel in the generator and if the 1 upper portion of the charge consists partly or wholly of coal, the heat of the gas serves to volatilize the volatile content of the coal and carry such volatiles with it.

At the same time, heavy oils or tars are 1 sprayed into the upper portion of the sec- 1 ondary generator 22 through pipe 27, valve 28 being opened, and these oils or tars are deposited on the hot coke in the generator. The upper portion of the fuel bed is at a 1 temperature suitable for volatilizing the most volatile fraction of this heavy liquid hydrocarbon, which is thus liberated. The remainder of the enriching material runs down through the coke toward the hotter 1

5 zones in the lower portion of the generator and additional less volatile fractions are liberated. The non-volatile residuum is finally solidified in the lower portion of the generator as coke. In this way the heavy oils or tars are volatilized in the most efficient manner by being gradually passed into zones of increasing heat.

10 The water gas generated in unit 11 passes through passage 23 into the upper portion of generator 22 where it is enriched by the volatiles liberated in this generator and the enriched gas goes through passage 36 to the superheater 37, passing down through the 15 highly heated brick work 38, which has been previously heated by the air blast gases. The enriching volatiles are largely fixed by the passage through the superheater and the enriched gas is taken off through the water 20 seal 46.

In down runs the steam is admitted through pipe 15 into the upper portion of generator 11, valve 16 being opened. Valve 24 is closed and valve 35' opened. Valve 42 25 may be adjusted as desired, all or part of the water gas being sent up through generator 22 to carry out the enriching volatiles. That portion of the gas which serves to carry off these volatiles passes down through the 30 superheater to fix them and meets the remainder of the gas in the bottom of the superheater.

35 Suitable temperatures may be maintained in generator 22, if desired, by passing in some air through the fuel bed in unit 22 during the gas making period in generator 11, thus making producer gas in unit 22, which gas carries with it the enriching volatiles and joins the water gas from unit 11 in the upper portion of unit 22.

40 The amount of coke formed in generator 22 from the non-volatile content of the enriching material will vary largely with such materials. It may be sufficient in amount 45 only for the combustion desired to maintain the mass of fuel in this generator at the proper temperature or it may provide an excess of coke which can be withdrawn for use in charging generator 11 or for other use.

50 It will be noted that the apparatus shown may be used to carry out widely varied processes. If generator 11 is shut down for any reason, it may be cut off from generator 22 by valves 24 and 35' and generator 22 may 55 be used for the production of water gas in the usual manner. This gas may be enriched by liquid hydrocarbon sprayed into the top of the generator through pipe 27.

60 The use of the two generators may also be reversed and the generator 11 used to liberate the enriching volatiles from heavy oils or tars, while water gas is made in generator 22. In this way an excess of coke formed from the solid residue of the liquid hydrocarbon may 65 be gasified without removal from the unit.

At times of heavy load both units may be used for the purpose of making water gas and enriching material may be sprayed in either generator or both generators if desired; or one generator only may be used for making 70 gas and carbureting or enriching it, but the generator must be of the agitating type so as to automatically prevent clogging of the fire bed by deposition of carbon from the oil and also prevent channeling and other irregular fire conditions.

To that end the rotating beam operating above the grate should preferably be as shown both upstroking and outstroking, serving 75 to agitate the fuel masses and prevent the formation of clinkers. This type of beam also prevents the formation of large solid masses of coke from the carbon residue of the enriching material and keeps the fuel masses broken up so that gases may pass up through 80 them substantially throughout their area. Ashes may be discharged as desired by means of the adjustable scoops and this discharge may be independent of the speed of rotation 85 of the beam.

90 While we have illustrated one preferred apparatus for carrying out our method and described certain ways of carrying out that method, it is to be understood that the method may be carried out by other forms of apparatus and in other ways; for instance, the up run water gas while hot may be introduced 95 at the bottom of the secondary generator, thus utilizing the sensible heat, and in combination with other types of gas producers or with any primary source of gas which it is desired to mix with or enrich with oil or gas. For instance, lean gases such as blast furnace gas may be introduced at the bottom of an agitated bed of coke on which oil is sprayed 100 from the top, as for example through passage 30 into generator 22, and we contemplate such changes and modifications as come within the spirit and scope of the appended claims.

105 What is claimed is—

110 1. The method of manufacture of mixed water gas and oil gas, which comprises utilizing a plurality of generators having solid fuel beds therein, agitating the fuel bed in one generator and making water gas therein, 115 gasifying liquid hydrocarbons in a second generator, making producer gas in said second generator, carrying out said gasified liquid hydrocarbons with said gas made in the second generator, mixing the gases made in the first and second generators, and passing the mixed gas directly through a superheater to fix the volatiles therein.

120 2. A process of making mixed water gas and oil gas, which comprises air blasting solid fuel beds to incandescence in two gas generators, then generating water gas in one generator by passing steam through the incandescent fuel bed and simultaneously agitating 125 the fuel bed, passing the heated water gas 130

up through the second incandescent fuel bed together with blast furnace gas and simultaneously agitating the second fuel bed, simultaneously admitting oil to the top of the second fuel bed and thereby vaporizing and gasifying the oil, passing the mixed water gas and oil gas through a heated fixing chamber and thereby fixing entrained oil vapors.

Signed at Chicago, Illinois, this 13th day of August, 1926.
